UNITED STATES PATENT OFFICE

FRANK TORKA AND WILLIAM V. E. TORKA, OF SEATTLE, WASHINGTON

COMBINATION LOCK

Application filed December 19, 1928. Serial No. 326,966.

The invention is an improvement in combination locks having rotatable discs, in that it provides a common means of operating a plurality of discs in combination, in which 5 the discs are operated by a common casing, which is rotated in first one direction and then in the other, and in which the device is provided with a means of locating the starting point from which the combination is formed, 10 a click arrangement by which a proper combination is indicated, and a simple means of changing the device to different combinations, after the lock has been opened by anyone knowing its previous combination.

15 The object of the invention is to provide an improved combination lock of a simple and inexpensive construction.

Another object of the invention is to provide a combination lock in which the combination may readily be changed by a person knowing the former combination.

Another object of the invention is to provide a combination lock having a plurality of rotatable discs in which the discs may be 20 rotated in opposite directions consecutively in order to be placed in their operative position.

Another object of the invention is to provide suitable separating means for the rotatable discs which will hold them firmly in position while the remaining discs are operated.

Another object of the invention is to provide means for providing a plurality of clicks to indicate to the operator the number of points the parts have moved.

35 A further object of the invention is to provide means for preventing the lock shaft of a combination lock rotating except when all of the parts are in their operative positions.

And a still further object is to provide a 40 combination lock which is of a comparatively simple and economical construction.

With these ends in view the invention embodies a lock shaft, a core in which the bolt is mounted, a plurality of rotatable discs 45 mounted upon the said core, friction spacing discs between the said former discs, a plurality of cams, rings and levers, a base, and a rotatable casing.

Other features and advantages of the invention will appear from the following de-

scription taken in connection with the drawings, wherein:—

Figure 1 is a front view of the lock with part broken away to show the inner formation of the base, and the location of the combination changing devices. 55

Figure 2 is a cross section through the lock.

Figure 3 is a section on line 3—3 of Figure 2, showing the mechanism in the normal or 60 zero position.

Figure 4 is an enlarged perspective view of the cam lever.

Figure 5 is an enlarged perspective view 65 of the dog.

Figure 6 is an enlarged perspective view of one spring pin.

Figure 7 is a view of the mechanism similar to Figure 3, showing the position of the 70 various parts when the discs are partly rotated.

Figure 8 is a side elevation of the lock with parts of the casing and base cut away to show the arrangement of the mechanism. 75

Figure 9 is a view showing one outer disc ring.

Figure 10 is a section through the outer disc ring.

Figure 11 is a section through the core 80 with the double wedge shaped member in a combination changing position, also showing one complete combination disc with its outer and inner ring and retarding spring pin, and on each side of the disc is shown one friction 85 plate.

Figure 12 is a view showing one inner disc ring.

Figure 13 is a section through the inner ring.

Figure 14 is a view of the casing assembly 90 showing the core with parts omitted.

Figure 15 is a view showing one friction plate.

Figure 16 is a section through the friction 95 plate.

Figure 17 is a perspective view of one crescent shaped cam.

Figure 18 is a perspective view of the lock 100 shaft.

Figure 19 is a section through the lock core. Figure 20 is an end view of the core.

Figure 21 is a side view of one ring spring. In the drawings the device is shown as it

5 would be made wherein numeral 1 indicates the flange locked core which is eccentrically mounted, numeral 2 the base, and numeral 3 a rotatable casing. The casing 3 constitutes the means for operating the lock. Numerals 4 and 5 indicate other combination disks which are also rotatable over core 1.

10 Each of the combination disks 4 and 5, and also the casing 3 is provided with one of the inner rings 6, as shown in Figures 12 15 and 13, and each of the rings 6 is provided with a recess 10 in which cams 11 are located, except when the shaft is turned to the position shown in Figure 14. In this position the cams are in the upper position and 20 lugs 45 on the shaft 7 extend into the recesses 10. The lugs 45, which are cam shaped as shown in Figure 18, are made integral with the shaft 7, and it will be noted that the shaft 7 is located in an eccentric bore and 25 recess 8 of the core 1, in such a way that in its normal position any part thereof does not extend outwardly of the periphery of the core 1.

30 The cam shaped lugs 45, on the shaft 7, are separated by grooves 9, which extend inward to the surface of the shaft.

35 The crescent shaped recesses 10, in the inner disk ring 6, form a complete circle with recesses 8, when placed in the normal position over the core 1, and permit the lock shaft with its lugs to revolve freely.

40 Crescent shaped cams 11 of the same width as shaft lugs 45, and also of the same shape as the recesses 10 are freely movable around the core with the disks when the disks are rotated and it will be seen that these cams allow the lock shaft to be revolved only when said cams are placed in an exact position coinciding with the path of the shaft lugs 45, and forming a perfect circle in combination.

45 The friction plates 12 are placed between the combination disks and casing 3, and are held stationary in relation to the core by 50 means of their crescent shaped openings, through which the core 1 extends, thereby preventing them rotating with the shaft.

The width of these friction plates is the same as that of the grooves 9, between the cam shaped lugs 45 on the shaft 7, and the slot 13, in said friction plates, is of the same width as the diameter of the lock shaft 7. These friction plates hold the outer and inner disk rings and the cams 11 in alignment, and at the same time exert friction on the disks, holding the resting disks in position while others are rotated. Part 14 of friction plate 12 fits in core recess 8, and therefore

60 65 these friction plates 12 also form channels for the freely moving cams 11 in the core recess 8.

The pawl 16 and the cam lever 17, which are pivotally mounted upon the inner side of the casing 3 by pins 15, engage notches 19 and 20, which are arranged in opposite directions on the disc 4. The pawl 16 only engages the disc 4, and the cam lever 17, which is somewhat thicker, extends partly over the disc 5, and it will be noted that an elongated recess 21 in the periphery of the disc 5, permits the cam lever 17 to drop and engage the notch 20 on the disc 4, while these discs are in the position shown in Figure 3. In revolving disc 5 the cam lever 17 passes out of the recess 21 and is elevated to the position shown in Figure 7, and at the same time the lug 22 on the lever 17 reaches up and engages the lug 23 on the dog 24, which extends downward as shown in Figure 8. The dog 24 is pivotally mounted on the disc 5 through a pin 25, and a projection 26 engages a notch 27 in a boss 28 on the inner side of the base 2, as shown in Figures 1 and 2 and indicated by dotted lines in Figures 3 and 7.

70 75 80 85 90 95 100 105 110 115 120 125 130 The spring 29 bears against one end of the dog 24, and a pin 31 limits the movement of the dog in the opposite direction. This end of the dog 24 engages a lug 30 secured to the inner wall of the casing 3, and thereby limits the movement of the casing in this direction when the dog 24 is in engagement with the notch 27 in the boss 28, as, when in this position the opposite end of the dog is raised to such a position it will engage the lug 30. This position constitutes the stop or starting position from which a combination is formed.

From this position the casing may be rotated in the opposite direction, and the lever 17, which is pivotally mounted on the casing 3 and held against the disc 4 by the spring 18 engages the notch 20 in the disc 4 and moves the disc therewith. The lug 22 on the lever 17 then engages the lug 23 on the dog 24 thereby lifting the dog up as far as the stop pin 31 on the disc 5 permits, thereby moving the opposite end of the dog inward so that it will not engage the lug 30. As a result of the limited movement of the dog the lug 22 on the lever 17 cannot pass between the lug 23 on the dog and the periphery of the disc 5, so that the disc 5 is also rotated therewith. Then by reversing the rotation of the casing 3 the pawl 16, engaging disc 4 only, moves the same therewith and the projection of the lever 17 passes out of the recess 21 of the disc 5 which is now stationary, and as the lever 17 is elevated its overlapping projection moves on the periphery of the stationary disc 5. In this movement the outer curve of the dog 24 has assumed a position which permits it to pass lug 30 in either direction, as shown in Figure 7.

The discs 4 and 5 have now formed an unbroken periphery so that as the casing 3 is again rotated in the opposite direction, leaving disc 4 stationary, the overlapping projec-

tion of the lever 17 may move around the periphery and the lug 22 is then elevated so that it passes by the lug 23 on the dog 24, as shown in Figure 7.

The casing may then revolve alone, and being a combination disc in itself, can be placed in any predetermined position. To place the lock back again in the starting position the casing 3 is rotated in a counter-clockwise direction as indicated by the arrow "A" in Figure 7.

As the casing rotates the pawl 16 first engages the notch 19 on the disc 4, and moving this disc with it places the notch 20 in line with the ratchet projection of the lever 17, which projection is still moving on the periphery of the stationary disc 5. As the movement is continued the projection of the lever 17 will pass into the recess 21 on the disc 5 and will fall into the notch 20, thereby placing lever 17 in its normal position, but with its lug 22 in the way of the lug 23 on the dog 24, thereby engaging the same and drawing the dog 24 with the disc 5 until the projection of the dog 24 is forced into the notch 27 on the base 3 by the spring 29.

At this point the end of the dog 24 is elevated again while its lug 23 assumes such an acute angle that the lug 22 on the lever 17 may pass over. An instant later the lug 30 on the casing 3 engages the end of the dog 24 and prevents any further rotation in this direction of the operating casing, as shown in Figure 3.

The combination may be changed as desired in the following manner:

As hereinbefore stated, the combination discs 4 and 5, and also the casing 3, consist of two concentric rings in which an inner ring 6 is identical in each disc. This ring is shown in detail in Figures 12 and 13. A recess 32 is provided to receive a pin 33 shown enlarged in Figure 6. The top of this pin is partly square, and when positioned in the recess 32 a stem 34 projecting therefrom extends through a hole 35 in the ring, as shown. The ring is also provided with an eccentric groove 36 in which a split spring ring 37, as shown in Figure 21, is placed. A slot 38 is provided in the pin 33, which corresponds with the ring groove 36 so that the spring may pass through the slot in the pin and resiliently hold the pin toward the lock core when the lock is assembled.

It will be noted that the core 1 is provided with a longitudinal slot 40, and a wedge member 39 having inclined surfaces corresponding with similar surfaces in the lower side of the opening in the core, is positioned in the opening 40 as shown in Figure 11, and when this wedge member is in the elevated position its surface completes the periphery of the core 1 as shown in Figures 3 and 7.

The pin 33 with its cylindrical stem 34 resting against the core extends beyond the

periphery of the ring 6 and into anyone of a plurality of evenly spaced notches 44 on the inner periphery of the discs thereby locking the discs in this particular position, as shown in Figures 3 and 7.

The wedge shaped member 39 and the lock shaft 7 are so arranged in the core 1 that they are opposite each other and the pin 33 is therefore opposite the crescent shaped notch 10 in the ring 6. When all of the combination discs are placed in such a position that the notches 10 coincide with the recess 8 in the core the pins 33 will then be in line and positioned over the wedge 39.

The lock shaft 7 may then be partly rotated so that its cams lock the discs to the core. A screw 41 holding the wedge 39 in position, may then be loosened and the wedge pushed forward until it drops into the position shown in Figure 11, thereby creating a channel in the core in which the stems of the pins 33 may extend. It will be noted that in this position the springs 37 will move the pins inward so that their outer ends will pass out of the notches in the ring or combination discs. These discs may then be free to rotate on the periphery of the inner rings 6.

The lock mechanism can now be operated as hereinbefore described, as the operating casing 3 may first be brought to the automatic stop and from this position any desired combination may be formed by rotating the casing first in one direction and then in another to selected positions which may be counted off by the clicks. It will be noted that a spring ball 42 is resiliently mounted in the outer edge of the casing 3, and the ball engages a plurality of notches 43 in the flange of the core 1, and as the casing is rotated the ball produces the clicks as it snaps from one notch to another. These notches 43 coincide exactly with the notches 44 in the combination disc rings.

After the new combination has been formulated the wedge member 39 is drawn back to its normal position by the screw 41, thereby elevating the pins 33 and forcing their outer ends into the new selected notches 44, and thereby hold the combination discs in a new combination which only will permit the lock to be opened.

A knob 47 is positioned on the outer end of the lock shaft 7, and is arranged so that a recess 46 therein can only correspond with the wedge member 39 when the lock is opened by some one knowing the previous combination and who can rotate the knob. This thereby prevents anyone tampering with the combination changing arrangement.

It will be understood that changes may be made in the construction without departing from the spirit of the invention. One of which changes may be in the general design or arrangement of the lock or of the discs, pawls, levers, dogs, and pins forming parts

thereof. Another may be in the use of any of these parts in a lock of any other type or description. Another may be in the use of a greater or lesser number of notches than shown, and still another may be in the use of a greater or lesser number of the combination discs.

It will also be understood that the inner end of the lock shaft may be formed in any 10 desirable manner and may be provided with means permitting the same being revolved complete or in part, in connection with various latch or locking mechanisms, or electric switches, etc. However, as this invention is 15 specific to the lock mechanism, such devices are not illustrated.

Having thus fully described the invention what we claim as new and desire to secure by Letters Patent, is:

20 1. In a combination lock of the character described, the combination with a casing rotatable over a flanged core eccentrically mounted upon a cylindrical base, of a plurality of discs rotatable over said core, stationary friction plates between the said discs, levers secured to the inside of the casing engaging the discs through which the discs may be rotated by the casing in opposite directions, a lock shaft having a plurality of cam 25 shaped lugs cooperating with similarly shaped recesses in the combination discs, freely moving cams also cooperating with the lugs and recesses, means for causing a click as the parts are rotated through consecutive 30 positions, means for moving all the discs to a common point by the casing when the casing is rotated in one direction, inner floating rings within the said combination discs, and means for holding the rings in relation to the 35 discs.

2. In a combination lock, the combination with a flanged core, of an eccentrically mounted casing, a base upon which the casing is rotatably mounted, a plurality of combination discs, a plurality of inner rings within the said discs, means for locking the inner rings in relation to the discs, a lock shaft extending through the said flanged core and having a plurality of cam shaped lugs extending therefrom, a plurality of cam shaped 40 members cooperating with the said lugs to complete a circle formed thereby, said lugs and cams being positioned within the inner rings of the said combination discs and arranged to permit the lock shaft to operate with the discs in a predetermined position only, and means for positioning the said discs by the casing.

3. In a combination lock of the character described, a base, a casing rotatably mounted upon the said base, a core extending into the said casing and base, a lock shaft eccentrically mounted in the said core, a plurality of floating combination discs rotatably mounted upon the said core, means for operating the said

discs by the said casing, and means for preventing the rotation of the core except when the discs are in a predetermined position.

4. In a lock, the combination of a plurality of rotatable discs, a rotatable casing, means for rotating the discs by the casing, holding rings within the discs, a core extending into said casing and discs, a lock shaft eccentrically mounted in said core, and means for preventing the rotation of the shaft except when the discs are in a predetermined position.

5. In a combination lock, the combination with a flanged core secured concentric to a cylindrical base, a casing rotatable on the said base, a plurality of encased discs rotatable over the said core, an eccentric lock shaft held by the discs, means for operating the discs by the casing to release the shaft, said base having a cylindrical concentric boss a ratchet notch in the periphery thereof on the inner side thereof, a dog engaging the said notch, said dog pivoted on the rotatable disc nearest the base, and a lug secured on the inner wall of the casing, said lug engaging one end of the said dog in its elevated position only.

6. In a combination lock, the combination with a core secured concentric to a base, a casing rotatable over the said core, a pawl pivoted on the inner side of the said casing, a cam lever pivoted on the casing opposite to the pawl, a spring actuating upon both the pawl and lever, an encased disc having oppositely positioned notches in the periphery thereof rotatable over the said core, said notches coinciding with the ends of the pawl and cam lever in certain positions, a second disc rotatable over the said core, a dog pivoted on the said disc, a lug on the said dog engaging a lug on the said cam lever, said second disc having an elongated recess in the periphery thereof in which a projection from the said cam lever drops in certain positions, said recess holding the cam lever in an elevated position as a projection at the end thereof passes over the periphery of the said second disc, a spring bearing against the said dog, and means for limiting the elevation of the dog when a lug thereon is engaged by a lug on the said cam lever.

7. In a combination lock, a base, a flanged core concentrically secured to the said base, an eccentric lock shaft extending through the core and base, a casing rotatable over the said flanged core and having a recess to receive the flange of the core, a plurality of discs rotatable on the said core, said casing and discs having concentric inner rings with crescent shaped recesses in their inner surfaces, crescent shaped cams normally resting in the said recesses, cams on the said lock bolt cooperating with the said crescent shaped cams to form complete circles, means for operating the said discs by the outer casing, and means whereby the said casing and discs co-

operate with the inner rings to position the inner rings to permit the lock shaft to rotate.

8. A combination lock as described in claim 7, in which the inner rings are provided with pins positioned opposite the crescent shaped recesses which engage recesses in the discs, and means for adjusting the position of the pins to change the position of the inner rings in relation to the discs and casing to change the lock combination.

9. In a combination lock of the character described, a base, a core extending from the said base, a rotatable casing mounted on the said core and base, a plurality of rotatable discs mounted within the casing upon the said core, a dog pivoted on one of the said discs, a lug on the said dog extending downward and partly over the periphery of the adjacent disc, a spring secured to the said disc and acting against the said dog to hold its lug against the periphery of the said adjacent disc, means for limiting the outward movement of the said dog and lug, said disc upon which the dog is mounted having a recess in the periphery thereof, a cam lever pivoted on the said rotatable casing, a lug on the said cam lever extending upward and positioned to engage the lug on the said dog, the lugs on the said dog and cam lever shaped to permit them to pass in one direction and to engage in the other so that they will engage when the lug of the dog is elevated to the limit of its movement.

10. In a combination lock, the combination with a plurality of discs rotatable over a flanged core having an eccentric bore, a lock shaft in the said bore, friction plates between the discs, said friction plates having crescent shaped openings through which the core passes to hold the plates stationary upon the core, said plates having elongated radial slots which pass over the said lock shaft, the ends of the said radial slots terminating at the eccentric bore for the lock shaft and of the same width as the lock shaft.

11. In a combination lock as described in claim 3, a spring ball in the said rotatable casing, a plurality of indentations in the periphery of the said core flange cooperating with the said ball thereby providing a click as the ball passes from one indentation to another, and similarly spaced notches in the inner surface of the said combination discs cooperating with the said clicks to determine the combination of the said lock.

12. In a combination lock, a base, a flanged core mounted upon the said base, compound discs rotatable over the said core, a casing with means for operating the said discs, said core having a recess, a double wedge member slidable in the said recess, the lower surface of the said recess having inclined surfaces cooperating with the said wedge member, and means for dropping the said wedge member

to free part of the said compound discs to change the combination of the said lock.

13. In a combination lock of the character described, a stationary core having a flange at one end, a base upon which the said core is mounted, a lock shaft eccentrically positioned in the said core, a plurality of inner rings mounted upon the said core, a plurality of rotatable discs mounted upon the said inner rings, friction discs between the said former discs, a rotatable casing, means for operating the discs by the casing, means for holding the inner rings in relation to the discs, means for changing the said holding means to change the combination of the said lock, and suitable cam shaped members on the said lock shaft cooperating with the said inner rings and arranged to operate only when the said inner rings are in a predetermined position.

14. In a combination lock as described in claim 12, a knob or handle at the face of the lock having a shaft extending therefrom through the lock core, and said knob or handle having a recess therein which coincides with the end of the said wedge member only when the lock is open.
